H. G. Manning

UNITED STATES PATENT OFFICE

LEONARDO BRUNO, OF WATERBURY, CONNECTICUT

WINDOW SHADE AND CURTAIN BRACKET

Application filed November 1, 1930. Serial No. 492,656.

This invention relates to window fixtures, and more particularly to an improvement in a combination shade and curtain bracket.

One object of this invention is to provide a device of the above nature having an adjustable shade supporting member slidably mounted upon a fixed support secured upon the top of a window frame.

A further object is to provide a device of the above nature in which the shade-supporting member has a spring-pressed lever passing therethrough, said lever having a tongue for interchangeably engaging in any one of a series of locking apertures formed in the fixed support.

A further object is to provide a combination bracket of the above nature which will be simple in construction, inexpensive to manufacture, easy to install, manipulate, and adjust, ornamental in appearance, and very efficient and durable in use.

With these and other objects in view there has been illustrated on the accompanying drawings one form in which the invention may be conveniently embodied in practice.

In the drawings:

Fig. 1 represents a plan view showing a pair of combination brackets located at the ends of a double window frame and a double-ended bracket located above the central stile, the shades and curtain rods being shown in dotted lines,

Fig. 2 is a front view of the same.

Fig. 3 is a fragmentary sectional view of one of the combination brackets, taken along the line 3—3 of Fig. 2, looking in the direction of the arrows, and showing the adjustable member for supporting the circular pintle at one end of a shade roller.

Fig. 4 is a sectional view, taken along the line 4—4 of Fig. 2, showing the complementary shade-supporting member for receiving the flat pintle of a shade roller.

Fig. 5 is a perspective view of one of the combination brackets for use upon the side of a window frame.

Referring now to the drawings in which like reference numerals denote corresponding parts throughout the several views, the numerals 10 and 11 indicate generally a pair

of complementary combination shade and curtain brackets adapted to be mounted on a double window frame 12 above the left-hand and right-hand stiles 13 and 14 respectively. A central stile 15 is also provided between the two windows 16 and 17.

In order to support the inner ends of a pair of shade rollers 18 and 19 and the bent-in extremities of two pairs of adjustable tubular U-shaped curtain rods 20 and 21, 22 and 23, respectively, provision is made of a double combination bracket 24, the construction of which is substantially the same as two of the end brackets 10 and 11 and connected by a central base 25. Each of the end brackets comprises a base 26, 26a, having a central row of apertures 27, 27a, preferably circular as shown, but which may be square or any other shape if desired. The outer extremity of each of the brackets 10 and 11 is provided with a pair of forwardly bent tongues 28, 28a, and 29, 29a, the latter being located below and inwardly offset from the former.

By means of this construction, the curtains supported by the tubular curtain rods 20 and 21, 22 and 23 will hang downwardly in the usual spaced relation with respect to the shades 18 and 19, as clearly shown in Fig. 1.

In order to permanently fasten the brackets 10, 11 and 24 to the upper lintel of the window frame 12, the inner ends of the brackets 10 and 11 and the outer ends of the bracket 24 are provided with centrally disposed screw holes 30 for receiving wood screws 31, while the bases of the tongues 28 and 28a are provided with screw holes 32 for receiving wood screws 33. The central combination bracket 24 is additionally supported by a screw 34 passing through an aperture in the central connecting base 25, as clearly shown in Figs. 1 and 2.

Each of the brackets 10, 11 and 24 are provided with opposed pairs of bent-over guide flanges 35 and 35a for receiving the base 36 of a sliding angle member 37 having an up-standing plate 38, the lower portion 39 of which is reduced in width and arranged to lie inside of the inturned guide flanges 35 and 35a. Each of the plates 38 is provided below the center thereof with a rectangular

aperture 40, the bottom edge of which is provided with a curled-over upstanding lug 41 forming a support for an inclined locking lever 42.

The lower end of the locking lever 42 is provided with a reduced tongue 43 which is adapted to be engaged in any one of the apertures 27, 27a, in the bases of the bracket members 10, 11 and 24. The upper end of the lever 42 is bent downwardly at 44 to form a seat for the upper end of a coiled spring 45, the lower end of which is seated upon an upwardly extending lug 46 forming integral with the sliding base 37 of the angle member 36 (see Fig. 3). The outer ends of the plates 38 are provided with the usual round holes 47 (Figs. 3 and 5) and rectangular slots 48 (Fig. 4) respectively, for receiving the usual round and rectangular pintles located on the opposite ends of the shade rollers 18 and 19.

Operation

In operation, assuming the parts to be in the position shown in the drawings, whenever it is desired to adjust the position of one of the sliding angle members 36, it will be merely necessary for the operator to press upon the downturned end 44 of the lever 42 to bring the tongue 43 out of the aperture 27 or 27a in which it is engaged. The sliding angle member 36 may then be moved manually in either direction in the guideways 35, 35a, of the bracket until the tongue 43 is in registry with any other of the apertures 27, 27a, in the base 26, 26a. Upon the release of the lever 42 the pressure of the spring 45 will cause said tongue 43 to move down into the aligned aperture 27, 27a, whereby the sliding member 36 will be positively held against further movement in either direction.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention what is claimed as new and for which it is desired to secure Letters Patent is:

- 55 1. In a shade bracket, a base for attachment to a window frame, an adjustable angle member having an outstanding plate and a base plate slidable on said bracket base, said outstanding plate having an aperture, a lever 60 passing through said aperture and having selective interchangeable engagement with said base at a plurality of points along its length, said aperture having a lug extending thereinto to form a pivot for said lever.
- 65 2. In a shade bracket, a base for attach-

ment to a window frame, an adjustable angle member having an outstanding plate and a base plate slidable on said bracket base, said outstanding plate having an aperture, a lever passing through said aperture and having selective interchangeable engagement with said base at a plurality of points along its length, said aperture having a lug extending thereinto to form a pivot for said lever, and a spring located between said base plate and the outer end of said lever for pressing the lower end of said lever against said bracket base.

In testimony whereof, I have affixed my signature to this specification.

LEONARDO BRUNO.
